UNITED STATES PATENT OFFICE

2,637,370

BARBER CHAIR

Nathan Peter Vizza, Michigan City, Ind.

Application November 19, 1951, Serial No. 257,009

9 Claims. (Cl. 155—25)

1

This invention relates to a barber chair and particularly for means for elevating the seat with respect to the rest of the chair.

In barbering operations it is customary to provide an adjustable seat in which the customer may be seated and elevated to the proper height for the barber to do the proper operations on the customer. For very short or juvenile customers it is customary to provide an adjustable seat which brings the head of the customer above the back of the chair so that the barber may conveniently perform the operation necessary thereon. While such an adjustable seat is satisfactory for small infants or younger children it is too high for most of the older children and they must sit on the seat, in which event the head of the customer may be below the back of the chair so that it is very inconvenient for the barber to perform the necessary tonsorial operation thereon.

This invention provides an adjustable seat which is adjustable with respect to the rest of the chair so that a customer of any size may be properly elevated with respect to the back of the chair so that the barber may conveniently perform the necessary operation thereon.

According to this invention this is accomplished by providing an elevating system adapted to be connected to the seat of the chair and provided with a base member for elevating the seat with respect to the frame of the chair.

It is accordingly an object of this invention to provide an improved barber chair.

It is a further object of this invention to provide an apparatus for elevating the seat of a barber chair with respect to the frame of the chair.

It is a further object of this invention to provide an automatic device for elevating the seat of a barber chair.

Other objects and many of the attendant advantages of this invention will become apparent from the following detailed description taken in conjunction with the accompanying drawings in which:

Figure 1 is a side elevation of a barber chair showing the seat adjuster with the seat in normal position;

Figure 2 is a similar view showing the seat in elevated position;

Figure 3 is an enlarged fragmentary vertical section of a portion of a chair showing the mounting of a seat adjuster;

Figure 4 is a cross-section taken substantially

2

on the plane indicated by the line 4—4 of Figure 3;

Figure 5 is an enlarged perspective view of a portion of the apparatus;

5 Figure 6 is a detailed view of a modified shoe according to the invention;

Figure 7 is a section taken substantially on the plane indicated by the line 7—7 of Figure 6;

10 Figure 8 is a view similar to Figure 4 and showing a modified form of locking arrangement;

Figure 9 is a vertical section taken substantially on the plane indicated by the line 9—9 of Figure 8;

15 Figure 10 is a view similar to Figure 4 and showing a further modification of the locking means;

Figure 11 is an enlarged fragmentary view of the locking mechanism according to Figure 10;

20 Figure 12 is a detail view showing further means of adjustably locking the chair seat in selected position;

Figure 13 is a cross section through a modified base collar; and

25 Figure 14 is a perspective view of the modified base collar.

In the exemplary embodiment of the invention, a barber chair has a base 10 in which is telescopically mounted an extensible standard 12 on which is mounted a chair frame 14 having a seat 16 and a back 18. The back 18 is fixedly arranged on the frame 14. Provided in what is known as an elevator chair, the standard 12 may be telescoped with respect to the base 10 by means of a suitable apparatus, usually a hydraulic jack having the usual operating handle 11.

30 In order to adjust the seat 16 with respect to the back 18 and the frame 14, I have provided a pair of side bars 20 and 22 which are rigidly anchored on the chair frame 14. Any suitable anchoring means of sufficient rigidity may be utilized,

40 however, I prefer to use a clamp and bolt arrangement 24 and 26 usually clamped on to a portion of the frame 14. The side bars 20 and 22 may extend completely across the front and back of the frame 14 or if the frame 14 has sufficient reinforcement adjacent the center thereof the bars 20 and 22 may terminate short of the front edge of the seat as illustrated in this particular embodiment. Each of the side bars 20

45 and 22 is provided with a pair of tubular guides 30 and 32 which may conveniently be constructed as a portion of a pipe nipple which is reamed out to a sufficient inside diameter and has lock nuts 34 and 36 to properly fasten the guides into the side bars 20 and 22.

55

Slidably mounted in each of the guides are extension rods 40 on the top of which is rigidly mounted the seat 16. Most of the barber chairs with which I am familiar are provided with a frame work on the bottom of the seat 16 and it is only necessary to provide openings therein and insert the tops of the rods 40 and provide lock nuts on each side of the frame 42 of the seat 16 to properly secure the seat to the tops of the rods 40. However, it may be possible that there are seats without such frame work in which case it would be necessary to provide a suitable frame for attachment to the rods 40.

The bottom ends of the rods 40 are likewise threaded and each pair of rods 40 is provided with a shoe 44 which is conveniently constructed as a loop of flat spring material. The shoes are provided with suitable openings and have inserted therein the lower ends of the rods 40 which are held in place by means of lock nuts 46 and 48.

A base collar 50 is mounted on the top of the base 10 and is rotatably mounted around the standard 12. The base collar 50 is of greater length than width so that it can be rotated in one direction so that it will fit between the pairs of shoes 44 and rotated in the other direction it will extend transversely across the path of motion of the shoes 44 so that when the chair is elevated the collar 50 may be rotated to pass under the shoes 44. When the collar 50 is rotated so as to intercept the path of travel of the shoes 44, the chair frame 14 may be lowered by means of the column 12. The extension rods 40 will slide in the guides 30 and 32 so that the seat 16 will remain stationary while the frame 14 is lowered.

While this provides sufficient adjustment between the back of the chair it is frequently desirable to elevate the entire chair to perform certain operations during the hair cutting or other tonsorial operation. Accordingly a locking means has been provided for securing the seat 16 in an elevated relation to the frame 14. The locking device comprises a pair of locking bars 52 and 54 which are overlying the side bars 20 and 22 and are longitudinally slidable with respect thereto. The locking bars 52 and 54 are connected to the side bars 20 and 22 by means of bolts 56 rigidly connected to the side bars 20 and 22 and slidably connected to the lock bars by means of the slots 58. The lock bars 52 and 54 are provided with a pair of key hole slots 60 and 62 having the large ends of sufficient size to slidably engage the extension rods 40. The extension rods 40 are provided with reduced sections 64 which are receivable in reduced portion 66 and the key hole slots 60 firmly anchor the rods 40 with respect to the lock bars 52 and 54. The lock bars are arranged for automatic operation by means of resilient devices such as spring 70 connected to an opening 72 in the locking bars and anchored in any convenient place on the frame 14 such as the lock bar 74. The lock bar 74 is conveniently attached to the side rods by means of the lock nut 36 on the guide 30. A pin 76 may be inserted in the lock bar 74 to prevent its rotation about the guide 30. The locking bars 52 and 54 may be returned to the unlocked position by means of a suitable manually controlled handle 80.

In operation of the device the chair is elevated to a maximum elevation by means of a hydraulic jack after which the collar 50 is turned to intercept the path of travel of the shoes 44. The chair is then allowed to return to its lowered position at which time the shoes will be intercepted by means of the collar 50 and raise the

seat with respect to the frame 14 and the rods 40 slide through the key hole slots 60 until the reduced portions 64 of the rods 40 will make contact with the reduced portion 66 of the key hole slots and the spring 70 will urge the locking bars into locking position so that the seat 16 is anchored with respect to the locking bars 52 and 54. After the seat 16 has been anchored with respect to the frame 14 the hydraulic jack may be used to raise the frame 14 together with the seat 16 so that the chair may be operated at any desired height.

Instead of the spring shoes 44 it is sometimes desirable to use a straight bar shoe 90 connected to the lower end of the rods 40 by means of connectors 92 having bi-furcated ends embracing the bar 90 and connected thereto by means of suitable fasteners such as rivet 94.

In barbing operations on people of less than normal stature it is frequently desirable to be able to adjust the seat at various heights with respect to the back. Accordingly, in the modification shown in Figures 8 and 9 an arrangement has been made which may be adjusted so that the seat 16 may take any desired height relation with respect to the back 18. According to this modification a seat frame 100 is provided with side bars 102 and 104 which are rigidly attached to a portion of the frame 100 by means of a clamp bar 106. The seat 16 is then mounted on the top of extension rods 108 substantially similar to the extension rods 40. However, the extension rods 108 are completely smooth and the locking arrangement is provided by means of locking bars 110 and 112 which extend rigidly between the shoes 114 and 116 and the seat 16. The bars 110 and 112 are provided with a plurality of openings 120 for engagement with the locking mechanism. The locking mechanism provides a base plate 122 extending across the side bars 102 and 104 substantially intermediate the extension rods 108. The latch mechanism comprises a rectangular frame 124 slidably mounted on the member 122. The frame 124 is provided with cross members 126 and 128 to which is rigidly attached keeper bars 130 and 132. Keeper bar 130 is slidably engaged in a guide 134 while the keeper 132 is slidably engaged in a guide 136. A spring 138 is connected to the plate 122 and to the rectangular sliding frame 124 so that the frame 124 is resiliently biased into locking position.

In the operation of this modification the frame 124 is moved backward against the influence of the spring 138 and locked in position by means of a latch 140 mounted on the frame 124 and engaging a detent 142, the latch 140 having a cut-out portion 144 for engaging the detent 142. The chair is then raised and the base collar rotated so that it is under the shoes 114 and 116 after which the frame is lowered to any desired height then the latch 140 is raised so that the spring will bring the keepers 130 and 132 into contact with the bars 110 and 112 so that they will engage one of the openings 120 therein. It will thus be seen that the chair seat can be adjusted to any desired position by means of the detents 130 and 132 engaging the openings 120 of the bars 110 and 112.

In the modification according to Figures 10 and 11 a locking mechanism is provided in the form of a sliding bar 150 mounted on brackets 152 attached to the side bars 102 and 104 preferably by means of the lock nuts 154 which secure tubular guides 156 in the side bars 102 and 104. The bar 150 is slidable on the brackets 152 by

means of the slot 153 and is provided with key hole slots 160 which selectively engage any of the reduced portions 162 of the locking bar 161.

Obviously the extension rods 193 could be replaced by slide rods 170 having a plurality of reduced portions 172 while locking bars 174 similar to the locking bars 52 can be used to selectively lock the extension rods 170 at any desired height, as shown in Figure 12.

An improved base collar indicated generally at 180 may be constructed by two pairs of angle irons secured together. A pair of long irons 182 and 184 are arranged in substantially fixed relation with a pair of short angle irons 186 and 188. Preferably they are arranged in rectangular formation and held in adjusted position by means of bolts 190 and 192. Obviously, this improved base plate may be turned so that the ends of the long angles extend transversely to the paths of travel in the path of travel of the shoes 114. Likewise, it can be rotated so that the short members are in the direction of travel so that the shoes 114 may travel past the base collar.

While for the purposes of exemplification particular embodiments of the invention have been shown and described according to the best present understanding thereof, it will be apparent that changes and modifications can be made therein without departing from the true spirit of the invention.

Having described the invention, what is claimed as new is:

1. In a barber chair having an extensible standard, a chair frame rigidly mounted on said standard, and a seat detachably mounted in said frame, a seat adjusting device comprising a pair of side bars rigidly attached to said chair frame, a pair of rod guides in each of said side bars, extension rods slidably mounted in said rod guides, said seat being mounted on the top of said rods, a shoe connecting the bottom ends of each pair of extension rods, a base collar rotatably mounted on said standard, said collar being engageable with said shoes to retain said seat spaced above said frame.

2. In a barber chair having an extensible standard, a chair frame rigidly mounted on said standard, and a seat detachably mounted in said frame, a seat adjusting device comprising a pair of side bars rigidly attached to said chair frame, a pair of rod guides in each of said side bars, extension rods slidably mounted in said rod guides, said seat being mounted on the top of said rods, a shoe connecting the bottom ends of each pair of extension rods, a base collar rotatably mounted on said standard, said collar being engageable with said shoes to retain said seat spaced above said frame, a pair of locking bars, said locking bars having key hole slots engaging said extension rods.

3. In a barber chair having an extensible standard, a chair frame rigidly mounted on said standard, and a seat detachably mounted in said frame, a seat adjusting device comprising a pair of side bars rigidly attached to said chair frame, a pair of rod guides in each of said side bars, extension rods slidably mounted in said rod guides, said seat being mounted on the top of said rods, a shoe connecting the bottom ends of each pair of extension rods, a base collar rotatably mounted on said standard, said collar being engageable with said shoes to retain said seat spaced above said frame, a pair of locking bars, said locking bars having key hole slots engaging said extension rods, and spring means

urging said locking bars into locking relation with said extension rods.

4. In a barber chair having a base standard, an elevator standard slidably mounted in said base standard and means for operating said elevator standard, a seat adjuster comprising a collar mounted on said elevator standard and rotatable about said elevator standard, a chair frame mounted on said elevator standard, a seat detachably mounted on said frame, a pair of side bars anchored on said frame, a pair of tubular guides secured in said side bars, extension rods slidably mounted in said guides, said seat being mounted on said rods, shoes on the lower ends of said rods, said collar being movable into and out of engaging positions with respect to said shoes, a pair of lock bars embracing said extension rods, key hole slots in said locking bars, a portion of said slots being of sufficient size to slidably engage the rods, reduced portions on said rods for engaging reduced parts of said slots.

5. In a barber chair having a telescoping standard, a chair frame secured on said standard, a seat, a seat adjusting device comprising a pair of side bars mounted in said chair frame, two pairs of rod guides mounted in said side bars, extension rods slidably mounted in said rod guides, a pair of shoes, each shoe being attached to the bottom ends of a pair of extension rods, said seat being supported on said extension rods, a collar rotatably mounted on said telescoping standard, said collar being rotatable into and out of engagement with said shoes, a lock bar anchored to said side bars and slidably in parallel relation thereto, key hole slots in said lock bars, said slots slidably engaging said extension rods, said extension rods having reduced portions for locking engagement with said slots.

6. In a barber chair having a base, an extensible standard telescopically mounted in said base, a chair frame secured on said standard, a seat, a seat adjusting device comprising two pairs of rod guides mounted on said frame, extension rods slidably mounted in said rod guides, a pair of shoes, each shoe being attached to the bottom ends of a pair of extension rods, said seat being supported on said extension rods, a base collar rotatably mounted on said standard, said collar being engageable with said shoes, lock bars anchored to said frame adjacent to said rod guides and slidable in transverse relation thereto, key hole slots in said lock bars, said slots slidably engaging said extension rods, said extension rods having reduced portions for locking engagement with said slots, resilient means urging said locking bars into locking engagement with said extension rods.

7. In a barber chair having a telescoping standard, a chair frame secured on said standard, a seat, a seat adjusting device comprising two pairs of rod guides mounted on said frame, extension rods slidably mounted in said rod guides, a pair of shoes, each shoe being attached to the bottom ends of a pair of extension rods, said seat being supported on said extension rods, a collar rotatably mounted on said standard, said collar being engageable with said shoes, lock bars anchored to said chair frame in proximity to said rod guides and slidable in transverse relation thereto, key hole slots in said lock bars, said slots slidably engaging said extension rods, said extension rods having reduced portions for locking engagement with said slots, resilient means urging said locking bars into locking engagement with said extension rods.

tension rods, and means for moving said locking bars to unlocking position.

8. In a barber chair having a telescoping standard, a chair frame secured on said standard, a seat, a seat adjusting device comprising a pair of side bars rigidly mounted on said frame, a pair of rod guides mounted in each of said side bars, extension rods slidably mounted in said guides, a pair of shoes, each shoe being attached to the bottom ends of a pair of extension rods, said shoes being constructed as loops of spring material, said seat being supported on said extension rods, a collar rotatably mounted on said standard, said collar being engageable with said shoes, lock bars anchored to said side bars and slidable in parallel relation thereto, key hole slots in said lock bars, said slots slidably engaging said extension rods, said extension rods having reduced portions for locking engagement with said slots.

9. In a barber chair having a base standard, an elevator standard slidably mounted in said base standard and means for operating said elevator standard with respect to said base stand-

ard, a seat adjuster comprising a collar slidably and rotatably mounted on said elevator standard, said collar engaging said base standard, a chair frame mounted on said elevator standard, a seat 5 detachably mounted on said frame, a pair of side bars anchored on said frame, a pair of tubular guides secured in said side bars, extension rods slidably mounted in said guides, said seat being mounted on said rods, shoes mounted adjacent the lower ends of said rods, said collar being movable into and out of the path of travel of said shoes.
